His Attorney.

UNITED STATES PATENT OFFICE

JOHN D. HILLIARD, OF SCHENECTADY, NEW YORK, ASSIGNOR TO GENERAL ELECTRIC COMPANY, A CORPORATION OF NEW YORK

FLUID LEVEL SYSTEM FOR CIRCUIT BREAKERS

Application filed July 1, 1929. Serial No. 375,189.

My invention relates to circuit breakers, and more particularly to a system for maintaining a predetermined fluid level in circuit breakers of the fluid-break type.

5 In the operation of circuit breakers of the fluid-break type, as oil circuit breakers, the interruption of large amounts of power involves considerable arcing during separation of the switch contacts, which are immersed in the oil bath, with resultant sudden formation of quantities of gases. Since the switch housing, or tank, is not entirely filled with oil, a considerable portion of the liquid may be thrown upwardly into the air space 15 by the expanding gases to impact with considerable force against the upper or cover section of the housing, or to exert pressure thereon, due to the cushioning effect of the air. In other words, the oil in being displaced into the air space above its normal level, creates internal pressures within the housing, which generally are of such order of magnitude as to determine the interrupting capacity of the switch. These internal pressures, for a given interruption of power, may be limited to safe values by maintaining the volume of the aforesaid air space above a certain minimum.

20 Due to the fact, however, that oil has a comparatively large coefficient of expansion, variations in temperature thereof even within normal operating ranges, cause considerable fluctuation in level of the oil, with consequent variation in the volume of the air space, and, in the case of air volume decrease, an increase in internal pressure for a given interruption of power.

Another problem involved in the fluctuation of the oil level is that the insulating bushing ground shield, which should always be immersed in the oil at its lower end to prevent static arcing, may be above the oil level and out of contact therewith.

25 A principal object of my invention is the provision of an improved system for maintaining substantially constant the fluid-level within a circuit breaker of the character above described, notwithstanding changes in volume of the fluid due to temperature variations, or other reasons.

Another object is the limitation in size of an oil circuit breaker for a given interrupting capacity, whereby the usual large air space above the oil level for permitting large fluctuations in the volume of the oil is rendered unnecessary.

30 For an understanding of my invention, reference is had to the following description taken in connection with the accompanying drawings wherein:

Figure 1 is an elevational view, partly in section, of circuit breaker structure.

35 Figure 2 is an elevational view, partly in section, of another form of circuit breaker structure.

40 Referring to Figure 1, electrical apparatus as an oil circuit breaker of a well known type is illustrated and comprises a main switch housing, or oil containing receptacle 1 and cover structure 2, upon which are mounted 45 insulating bushings 3, for the conductor studs. Depending from the cover structure 2 and extending within the switch housing, are the usual ground shields 4, whose lower ends are immersed in the oil body 5. Likewise 50 immersed in the oil body in the usual manner is the current carrying and contact structure of the switch comprising a movable bridging member 6, co-acting with stationary contacts (not shown) within explosion chambers 7.

45 A liquid level sight gauge 8 is mounted upon the switch housing at the desired oil level. An overflow conduit 9, disposed adjacent the aforesaid desired level, and in 55 communication with the interior of the housing, discharges through a restricted opening 10 at its lower end into a reservoir 11 provided with an atmospheric vent 12. Suitably 60 mounted with respect to the reservoir is a motor 13 adapted to actuate through shaft 14, a fluid impeller or actuating means of any suitable type, for a purpose hereinafter described. In the present instance the impeller 15 is of the centrifugal type. A second 65 circuit 16, whose lower end is in communication with the fluid impeller 15, is provided with a valve 17, and a sight feed gauge 18, from which discharge of liquid may take 70

place through conduit 19 into the interior of the switch tank.

Motor 13 may be energized and controlled in any suitable manner, and in the present instance is provided with a manual control switch 20, which may be located remotely with respect to the circuit breaker, as in the operating room of the sub-station or power house.

Since in operation the gas or air-containing space in the upper part of the switch housing should not be less than a certain minimum value, depending upon the particular construction of the circuit breaker, and the power interrupting capacity of the switch, a very large air space, in the event that no liquid level regulating means are provided, must be used in order that fluctuations in the oil level due to the relatively large coefficient of expansion of oil, may not reduce the air space below its required minimum, or expose the lower ends of the ground shields upon contraction of the oil body. This problem is very readily understood when it is realized that the coefficient of expansion of oil is approximately $\frac{1}{10}$ of 1 percent of its volume for each degree centigrade.

Upon interruption of large currents, the gases formed by the power arc tend to move a portion of the oil body with great velocity towards the top of the circuit breaker, and to create very high internal pressures therein. The air space beneath the cover 2 accordingly acts as a buffer, or cushioning means. When the cushioning effect of the air space is reduced below a certain point, the internal pressures so set up within the circuit breaker are abnormally high and may result in considerable damage thereto.

Considering now the existence of an abnormally low oil level, as where the level is below the lower ends of ground shields 4, a further source of danger due to secondary explosions within the switch housing is encountered. In other words, when the ground shields are out of contact with the oil, there is possibility of static arcing with the resultant ignition of the highly inflammable gases which generally collect within the air space, particularly immediately after interruption of the circuit. Obviously, such secondary explosions may be of such violent nature that considerable damage to the equipment in question may result.

By my invention, provision is made for maintaining the level of the oil body substantially constant, whereby the lower ends of the ground shields may at all times be submerged in the oil, and wherein the air space need not be of excessive size, notwithstanding the tendency for large fluctuations in volume of the oil within the switch housing for any reasons whatsoever.

To this end, the overflow conduit 9 discharges into the reservoir 11 upon rise of the

oil level beyond the position illustrated in Fig. 1. The restricted opening or vent 10 in the lower end of the discharge conduit prevents sudden expulsion of oil into reservoir 11 upon interruption of the circuit. Motor 13, which may be run either continuously or at the will of the operator, actuates the fluid impeller 15 to force oil from the reservoir by way of conduit 16, sight gauge 18 and conduit 19, back into the switch housing. Accordingly, a continuous circulation may be effected to maintain the oil level substantially constant.

Assuming for the purpose of example, that the oil body contracts in volume due to low temperature, the oil level will drop below the opening of the discharge conduit 9, so that reservoir 11 does not receive oil from the main body. However, due to the storage capacity of the reservoir, the fluid impeller will act to force oil through conduit 16, etc., back into the switch housing to raise the level again up to the discharge conduit opening. Upon increase in temperature, the oil level rises above the opening of discharge conduit 9, thereby permitting flow of excess oil into reservoir 11. The storage capacity of reservoir 11 is such that its oil level will not fall below a certain minimum, as 11a, for extreme low temperatures, nor will it exceed a maximum level, as 11b, at comparatively high temperatures. Accordingly, it will be noted that the variations in volume of the oil body occur within reservoir 11, thereby maintaining the volume in the main switch housing substantially constant.

It should be noted at this point that both the discharge and return conduits are located in proximity to the normal oil level. This arrangement permits maintenance of the oil level with minimum disturbance of the main body. Due to the fact that sludge or other sedimentary matter frequently accumulates in the bottom of the switch housing, it is obvious that currents of oil near the lower part of the switch housing might stir up this sludge to cause it to mix with the rest of the oil body. Such disturbance of the sludge is obviously objectionable and should be avoided.

Referring to Fig. 2, there is shown a modified form of the above described system wherein a circuit breaker similar to the one previously described is provided with means for regulating the oil level in response to variations thereof. To this end, a chamber 21 communicating by way of vent 22 with the interior of the switch housing 1, and mounted exteriorly of the housing is provided with a float member 23 having an operating stem 24 extending through a conduit 25 and terminating in a valve member 26, at the lower end thereof. Conduit 25 provides means of communication between chamber 21 and a reservoir 27, the conduit being provided with

a restricted opening or vent 28, for the purpose of preventing sudden expulsion of oil from the main switch housing. As in the previous instance, a motor 29 for driving a 5 centrifugal fluid impeller 30 is mounted with respect to reservoir 27 and when energized tends to force oil from the lower part of reservoir 27, through the impeller discharge opening 31, into a valve chamber 32 and upwardly through conduit 25 into chamber 21, in the event that valve 26 is open. An atmospheric vent 33 is adapted to maintain the interior of reservoir 27 and the interior of the switch housing at atmospheric pressure.

15 Motor 29 is adapted to be energized from a suitable source of power 34—35, through lead conductor 36 and a conductor 37 having interposed therein a control switch responsive to variations in the oil level within the main 20 switch housing. In the present instance the control switch comprises a float chamber 38 in communication with the main oil body below its normal level through conduit 39, and provided with a float member 40 carrying 25 a pair of contacts 41 and 42 adapted to be bridged by contacts 43 and 44. Variation of oil level within housing 1 accordingly produces a corresponding variation of the level within float chamber 38 with attendant rise 30 and fall of float 40. Contacts 41 and 42 are maintained in alignment with contacts 43 and 44 through the guiding action of the insulating bushings 45 and 46. Upon an increase in height of the oil level, float 40 acts 35 to separate the contacts 41 and 42 from the bridging elements to interrupt the motor circuit and thereby stop the fluid impeller, and vice versa, lowering of the oil level serves to bring float 40 and its associated contacts into 40 engagement with the bridging structure to complete the motor circuit and cause actuation of the fluid impeller.

The opening 22, which is disposed at the normal oil level, permits overflow into chamber 21, and from there into reservoir 27 upon increase in volume of the oil due to increase in temperature. At the normal oil level, float 40 maintains the motor circuit open so that the fluid impeller is idle. Assuming further 45 that the oil volume continues to increase, the excess oil will slowly flow by way of chamber 21, conduit 25 into reservoir 27, thereby preventing rise in the oil level above vent 22. Upon lowering of the oil level below vent 22, float 40 descends to complete the motor circuit and to start operation of impeller 30. In this event oil will flow from reservoir 27 50 upwardly through conduit 25, which was formerly the discharge conduit, into chamber 21, and through vent 22 into the switch housing. Impeller 30 continues to replenish the main oil body until its level has again been restored to approximately the level of vent 22, at which time float 40 will have broken the motor circuit. In the event that the float operated control switch should fail for any

reason to interrupt the motor circuit, the increase in oil level due to continued energization of impeller 30, causes the float operated valve 26 to rise vertically and close to prevent further discharge through conduit 25. 70 For the purpose of obtaining auxiliary or alternate control of the motor, pressure operated means may obviously be associated with the valve chamber 30 so that the increase in pressure therein due to closure of valve 26 75 may be effective to actuate an alarm, or even to interrupt the motor circuit itself.

The oil level in the present modification is likewise regulated near its normal level, thereby preventing agitation of the main oil 80 body and the stirring up of sludge or other sediment.

It shall be understood that various changes may be made in the systems herein described and illustrated without departing from the 85 spirit of my invention, for example, a plurality of circuit breakers may be connected to a single reservoir and fluid impeller, and a uniform oil level for all of the circuit breakers may be accordingly maintained. 90

What I claim as new and desire to secure by Letters Patent of the United States, is:

1. Electrical apparatus including an enclosed oil-containing receptacle and current carrying structure immersed in said oil, and means maintaining a predetermined level of said oil comprising a reservoir containing oil, the capacity of said reservoir being at least equal in volume to the difference between the maximum and minimum volumes 100 of the oil normally contained within said receptacle, a conduit in communication with said receptacle at said predetermined level for discharging oil into said reservoir, and fluid actuating means for forcing oil from 105 said reservoir into said receptacle at a point adjacent said level whereby agitation of the oil body is precluded.

2. The combination with an oil circuit breaker comprising an enclosed oil-containing receptacle, and contact structure immersed in said oil, the level of said oil normally spaced a predetermined distance from the top of said receptacle, of an overflow conduit communicating with said receptacle 110 at said normal oil level, a reservoir into which said conduit may discharge upon increase in volume of the oil within said receptacle, and fluid actuating means adapted to discharge oil from said reservoir into said receptacle at a point adjacent said level in response to decrease in volume of the oil below its normal level. 115

3. The combination with an oil circuit breaker comprising an enclosed oil-containing receptacle and contact structure immersed in said oil, the level of said oil normally spaced a predetermined distance from the top of said receptacle, of a conduit communicating with said receptacle at said nor- 120 125 130

mal oil level, said conduit having a restricted opening at its discharge end for preventing sudden expulsion of oil from said receptacle, a reservoir into which said conduit may discharge upon increase in volume of the oil within said receptacle, and fluid actuating means adapted to discharge oil from said reservoir into said receptacle for maintaining the level of said oil at said predetermined level.

10 4. The combination with an oil circuit breaker, comprising an enclosed oil-containing receptacle, contact structure immersed in said oil, of means for maintaining a normal level of oil below a predetermined distance from the top of said receptacle comprising a discharge conduit disposed at the normal level of the oil, a reservoir into which said conduit may discharge, fluid actuating means adapted to discharge oil from the reservoir into said receptacle by way of said conduit, a fluid actuated valve closing said conduit upon increase of the oil level above its normal level, and fluid actuated means controlling energization of said actuating means in response to variations in said oil level.

5. The combination with an oil circuit breaker, comprising an enclosed oil-containing receptacle, and contact structure immersed in said oil, of means for maintaining a predetermined level of oil within said receptacle, comprising a conduit disposed at the normal level of the oil, a reservoir with respect to which said conduit is in communication, centrifugal fluid impeller means adapted to discharge oil from the reservoir into said receptacle by way of said conduit, motive means for said impeller, and a float operated switch for controlling energization of said motive means in response to variations in said oil level.

6. Circuit interrupting apparatus including an oil circuit breaker having an enclosed oil-containing receptacle and contact structure immersed in said oil, and means for maintaining a normal level of said oil at a predetermined distance from the top of said receptacle notwithstanding increase or decrease in volume of the oil comprising a conduit in communication with said receptacle at said normal level for discharging oil in response to increase in volume of the oil, and fluid actuating means for causing flow of oil into said receptacle adjacent said normal level for compensating for decrease in volume of the oil.

7. Circuit interrupting apparatus including an oil circuit breaker having an enclosed oil-containing receptacle and contact structure immersed in said oil, and means for maintaining a normal level of said oil notwithstanding increase or decrease in volume thereof comprising a reservoir containing oil, the capacity of said reservoir being at least equal in volume to the difference between the

maximum and minimum volumes of the oil normally contained within said receptacle, a conduit in communication with said receptacle adjacent said normal oil level for discharging oil into said reservoir, and fluid-actuating means for forcing oil from said reservoir into said receptacle at a point adjacent said normal level whereby agitation of the oil appreciably below said normal level is precluded.

8. Circuit interrupting apparatus including an oil circuit breaker having an enclosed oil-containing receptacle and contact structure immersed in said oil, and means for maintaining a normal level of said oil notwithstanding increase or decrease in volume thereof comprising an overflow conduit in communication with said receptacle adjacent said normal oil level, a reservoir into which said conduit may discharge upon increase in volume of the oil, the capacity of said reservoir being at least equal in volume to the difference between the maximum and minimum volumes of the oil, and fluid-actuating means including a second conduit for forcing oil from said reservoir into said receptacle at a point adjacent said normal level thereby compensating for decrease in volume of said oil.

9. The combination with a tank partially filled with oil and electrical apparatus immersed in said oil, of means maintaining a predetermined oil level comprising a conduit in communication with said tank at said level, a reservoir in communication with the other end of said conduit, the oil discharging through said conduit into said reservoir upon expansion of the oil above said level, and fluid actuating means for forcing oil from said reservoir through said conduit and into said tank upon recession of said oil below said level.

10. The combination with a tank partially filled with oil and electrical apparatus immersed in said oil, of means maintaining a predetermined oil level comprising a conduit in communication with said tank at said level, a reservoir in communication with the other end of said conduit, said conduit discharging oil from said tank into said reservoir when said level is exceeded, fluid actuated means for forcing oil from said reservoir through said conduit and into said tank when the oil recedes from said level, and a float operated valve closing said conduit when said level is exceeded.

In witness whereof, I have hereto set my hand this 26th day of June, 1929.

JOHN D. HILLIARD.
